(57) **CLAIM**

The ornamental design for a rotatable teleidoscope viewing stand, as shown and described.

DESCRIPTION

FIG. 1 is a perspective view of a rotatable teleidoscope viewing stand showing the new design.

FIG. 2 is a first side view of a rotatable teleidoscope viewing stand showing the new design.

FIG. 3 is a second side view of a rotatable teleidoscope viewing stand showing the new design.

FIG. 4 is a front view of a rotatable teleidoscope viewing stand showing the new design.

FIG. 5 is a rear view of a rotatable teleidoscope viewing stand showing the new design.

FIG. 6 is a top view of a rotatable teleidoscope viewing stand showing the new design; and,

FIG. 7 is a bottom view of a rotatable teleidoscope viewing stand showing the new design.

The broken lines depict portions of the rotatable teleidoscope viewing stand that form no part of the claimed design.

1 Claim, 3 Drawing Sheets
